UNITED STATES PATENT OFFICE.

WALTER L. CONWELL, OF MONTCLAIR, AND WILLIAM I. THOMSON, OF NEWARK,
NEW JERSEY.

GENERATOR DRIVING.

Application filed December 5, 1918. Serial No. 265,327.

To all whom it may concern:

Be it known that we, WALTER L. CONWELL and WILLIAM I. THOMSON, citizens of the United States, the former a resident of Montclair, and the latter a resident of Newark, both in the county of Essex and State of New Jersey, have invented an Improvement in Generator Driving, of which the following is a specification.

10 This invention relates to railway cars and with regard to the more specific features thereof, to a method and to means for operating car accessories.

One of the objects of the invention is to 15 provide a simple and reliable method for insuring under adverse conditions, the proper operation of car accessories that are connected to the outside of the car.

Another object is to provide practical 20 means, automatic in action, for compelling the effective rotation of generators of the type propelled from car axles, even when the driving belt is covered with ice.

Another object is to provide means of the 25 above type, which shall operate properly and effectively regardless of the speed or direction of locomotion of the car.

Another object is to provide means of the 30 above type, convenient in control and unlikely to fail in operation.

Other objects will be in part obvious, in part pointed out hereinafter.

The invention accordingly consists in the 35 features of construction and operation, combination of elements, arrangement of parts, and steps of the method, which will be exemplified in the construction and operation hereinafter set forth, and the scope of the application of which will be indicated in the 40 following claims.

In the accompanying drawings, wherein 45 is shown one or more of various possible embodiments of the several features of this invention, Fig. 1 is a fragmentary sectional view of a railway car with our apparatus applied thereto. Fig. 2 is a side view of our sanding apparatus on a railway car. Fig. 3 is a top view of a part of our apparatus the cover being removed. Fig. 4 is a transverse

50 sectional view taken along the line 4—4 of Fig. 3, Fig. 5 is a transverse sectional view taken along the line 5—5 of Fig. 3 and Fig. 6 is a diagrammatic view showing the electric circuits.

55 Similar reference characters refer to simi-

lar parts throughout the different views of the drawings.

Referring now to Figs. 1, 2 and 6 of these drawings, there is shown a part of a railway car 1, within a locker 2, of which is enclosed 60 a reservoir 3, preferably of funnel shape, containing sand 4. Mounted on the car axle 5, is the driving pulley 6, connected by a belt 7 to a generator 8, of any desired construction, employed preferably for feeding a storage battery 9, and for operating in parallel with said storage battery to maintain the electric lamps 10, or other current consuming apparatus on the railway car supplied with current. This generator 8 may be regulated by any desired method, no particular method being disclosed in this application, as our invention does not reside in the regulation of the generator taken by itself. 65

The funnel 3 is preferably connected by a 70 sand pipe 11 to a point 12 adjacent to the pulley 6, and in the plane of the driving belt 7, in order to supply sand to the driving surface of the belt whenever required for the purpose of preventing the belt from slipping 75 idly with respect to the generator without driving it.

In Figs. 3, 4 and 5 we have shown the preferred form of connection between the reservoir and the conduit 11. Referring to these 80 figures, we have shown a fragmental view of an electric motor 26, whose driving shaft 51 passes into a gear box 52, in which is contained power reduction means to be described more fully below. 85

From the delivery end of this power reduction means, there extends a shaft 53 leading preferably into a rectangular compartment 54. This compartment is preferably provided with an opening 55 at its top, into 90 which is secured, preferably by screw threading the lower end of reservoir 3 conformed as a conduit 56 through which sand may pass.

Projecting preferably from the bottom of 100 the compartment 54, and secured in threaded relation out of alignment with conduit 56, is the delivery conduit 11 leading to the belt in the manner above described.

Connected to the free end of shaft 53, 105 preferably by a sleeve 58, keyed or splined to the shaft, there is a conveyer preferably in the form of a rectangular vane 59 whose sides come into close proximity to the lateral interior faces of compartment 54. The vane 110

59 and the securing sleeve 58 are preferably formed integrally.

Extending downwardly from the top of compartment 54 and in proximity to that side of conduit 56 lying toward conduit 11, there is a partition 60 which extends part way into the compartment, terminating in an edge 61.

The path of the vane 59 when rotated by the motor, is indicated by dotted lines in Fig. 5, and the partition 60 is deflected as shown, so as to offer no obstruction to the free rotation of this vane. Normally, the sand from the reservoir will flow freely down conduit 56, resting on the bottom of compartment 54, or platform 71. It will assume an angle of repose past edge 61, indicated by line 62, in Fig. 5. In operation, as the vane is slowly rotated by the motor, through the transmission within the gear box 52, the edge of said vane will intersect the pile of sand and will convey substantially all that part of the pile which lies in its path, from the platform to the conduit 11 to be delivered to the belt.

Part of the sand having been removed, the sand will again endeavor to resume its angle of repose, and consequently a quantity of sand equal to that which was removed by the vane, will move down from the reservoir through the conduit 56 to the platform, restoring the original angle of repose, whereupon the cycle is repeated. Thus, for each rotation of the vane 59 about its axis, a predetermined quantity of sand will be conveyed by vane 59 from the platform by way of conduit 11 to the belt, and during said cycle, the angle of repose of the sand will be restored by the delivery of a quantity of sand to the platform from the reservoir equal to that which has been removed.

It is desirable to cause the vane to rotate at a speed in the order of one rotation per minute. We do this by stepping down the speed of the motor 26 through a power reducing means producing the proper power ratio. We have shown our preferred form of power reducing means in Figs. 3 and 4.

This consists preferably of a worm 63 connected to shaft 51 and driving a worm wheel 64 connected to a shaft 65, which shaft is in turn mounted within a standard 66, having a bearing 67 for said shaft, said standard being mounted on the bottom 68 of the gear box.

On the side of standard 66, opposite gear 64, there is rigidly mounted on said shaft a worm 69, which worm engages with and drives a worm wheel 70, to which shaft 53 is preferably connected to be driven thereby.

Referring now to Fig. 6 the motor 26 is preferably provided with a shunt field 44 to secure substantial constancy of speed of the motor.

65 This motor is preferably arranged to de-

rive its current from the generator 8, being connected for this purpose to the generator or the mains on the generator side of the automatic switch 45. A hand switch 46 is provided in the circuit for connecting the motor and generator serving to cut the motor out of operation when its action is undesired. This hand switch is arranged in any desired manner so as to be accessible from the inside of the car, and whenever it is closed and the generator is driven even at slow speed, it will energize the motor sufficiently to start its action.

To maintain the sand in dry condition, the funnel 3 is preferably located in locker 2 in proximity to steam heating pipes 47.

The operation of the above described embodiment of this invention is substantially as follows: Assuming the car to be located in a region of inclement weather, so that the belt 7 is covered with ice, the slipping of said belt with consequent inoperativeness of the generator 8 is prevented, as follows: When it is desired to feed sand to the belt, the switch 46 is closed and even slow speed of the generator will energize the motor 26 sufficiently to rotate the conveyor vane 59 through the mechanism hereinbefore described. The vane will thereupon be set into continuous slow rotation. As the edge of the vane 59 intersects the surface of repose 62, it will scoop out a definite quantity of sand, which is effectively conveyed thereby into alignment with conduit 11, through which it flows to the belt 7. The lateral faces of compartment 54 prevents any substantial portion of the sand ladled out by the vane from being lost in transit. Part of the sand having been removed from the pile on platform 71, the sand will again endeavor to recover its angle of repose, and consequently a quantity of sand equal to that which was removed by the vane will move down from the reservoir to the platform, restoring the original angle of repose. By the well known action of sand, the slipperiness of the belt will be overcome so that it may effectively transmit power from the pulley 6 to the generator 8. As the vane continues its rotation, the cycle of transporting a quantity of sand from the platform to conduit 11 feeding it to the belt and permitting the force of gravity to restore the angle of repose will be repeated periodically. Therefore in the operation of the car, regardless of extreme weather conditions, the belt will be periodically supplied with a quantity of sand to effectively prevent slipping.

The motor being of the shunt wound type, will operate at substantially constant speed when connected to the generator. The sand will therefore be supplied to the belt at a constant rate regardless of the speed or direction of locomotion of the car.

If manual means were relied upon to sand

the belt, it is obvious not only that there would be difficulty in keeping the proper quantity of sand supplied to the belt at all times when sand is desirable, but that the 5 forgetfulness of the man designated to attend to this matter would have to be contended with.

If it be attempted to secure sanding of the belt by mechanical automatic means, operated 10 from the car axle, as for instance by having the sand come by centrifugal force through a hole in the face of the pulley, the rate of supply of sand would increase greatly as the car speeds up, with a consequent throwing out of all of the sand within 15 a short time. In this case the system may also at times be entirely inoperative, because the hole may be plugged up and no sand escape.

20 It is to be understood that although we have shown an electrical arrangement of a specific kind for operating the sand conveying means, other mechanical or electrical arrangements may be employed to advantage, but it is to be understood that there are special benefits in the use of the specific arrangement shown and described.

It will thus be seen that there is herein described a method and apparatus for carrying out the method, in which the several features of this invention are embodied, which method and apparatus in their action attain the various objects of the invention and are well suited to meet the requirements 35 of practical use.

As many changes could be made in the above construction, and many apparently widely different embodiments of this invention could be made without departing from 40 the scope thereof, it is intended that all matter contained in the above description or shown in the accompanying drawings shall be interpreted as illustrative and not in a limiting sense.

45 Having described our invention, what we claim as new and desire to secure by Letters Patent, is:—

1. In a belt sanding device for railway cars and the like, in combination a driving 50 belt, a source of sand or the like, and means actuated as a result of the locomotion of the car, for periodically supplying a quantity of sand to said belt.

2. In apparatus of the character described, 55 in combination a car axle, a driving belt connected thereto, a source of sand or the like, a motor deriving its energy as a result of the rotation of said car axle, and means controlled by said motor for causing sand to be 60 supplied from said source to said belt, to prevent substantial slipping thereof in use.

3. In apparatus of the character described, 65 in combination, a car axle, a driving belt connected thereto, a source of sand or the like, a motor deriving its energy as a result

of the rotation of said car axle, and means controlled by said motor for causing a quantity of sand to be supplied at intervals from said source to said belt, to prevent substantial slipping thereof. 70

4. In apparatus of the character described, in combination, a car axle, a belt driven therefrom, an electric generator driven by said belt, a source of sand, an electric motor deriving current from said generator, and means controlled by said motor for causing a quantity of sand to be supplied periodically from said source to said belt, to prevent substantial slipping thereof. 75

5. In apparatus of the character described, in combination, a car axle, a belt driven therefrom, an electric generator driven by said belt, an automatic switch for making and breaking the external circuit of said generator, a source of sand, an electric motor 80 connected to said generator on the side of said automatic switch distant therefrom, and means controlled by said motor for causing a quantity of sand to be supplied at intervals from said source to said belt to prevent 85 substantial slipping thereof. 90

6. In a belt sanding device for railway cars and the like, in combination, a driving belt, a source of sand or the like, and means for supplying said sand to said belt during 95 locomotion of said car, at a substantially uniform rate, regardless of the speed of said car.

7. In a belt sanding device for railway cars and the like, in combination, a driving belt, a source of sand or the like, and means 100 actuated as a result of the locomotion of the car, for supplying said sand to said belt at a substantially uniform rate during said locomotion, regardless of the speed or direction of motion of said car. 105

8. In a belt sanding device for railway cars and the like, in combination, a driving belt, a source of sand, a substantially constant speed motor, means for causing said motor to control the rate of supply of said sand to said belt, and means for causing said motor to operate at its said substantially constant speed when the car is in locomotion. 110

9. In a belt sanding device for railway cars and the like, in combination, a driving belt, a source of sand, a shunt wound electric motor, means for causing said motor to control the rate of supply of said sand to the driving surface of said belt, and a current generator energized by the locomotion 115 of said car, for supplying said motor with power. 120

10. In a belt sanding device for railway cars and the like, in combination, a car axle, a lighting generator, a belt connecting said generator to be driven from said axle, a reservoir adapted to supply sand to the driving surface of said belt, and a substantially constant speed shunt wound electric motor deriving current from said generator for 125 130

controlling the rate of supply of said sand to said belt.

11. In a belt sanding device for railway cars and the like, in combination a car axle, 5 a lighting generator, means for maintaining substantially constant for varying speeds a function of the output of said generator, a belt connecting said generator to be driven from said axle, a reservoir 10 adapted to supply sand to the driving surface of said belt, and an electric motor deriving current from said generator, said motor being of the type that runs at substantial constant speed when supplied by 15 said generator, said motor controlling the rate of supply of said sand to said belt.

12. In a belt sanding device for railway cars and the like, in combination, a car axle, 20 a generator, a storage battery adapted to be charged thereby, an automatic switch between said generator and said battery, an electric motor connected to said generator on the side of said switch remote from said battery, and a sand reservoir, connected to said 25 belt, said motor controlling the supply of sand to said belt.

13. In a belt sanding device for railway cars and the like, in combination, a driving belt, a source of sand connected to the driving 30 surface of said belt, means for causing a periodic supply of sand to said belt, and means for converting mechanical energy of the moving car to electrical energy and back to mechanical energy to operate said 35 first means at a substantially uniform rate regardless of the speed of said car.

14. In apparatus of the character described, in combination, a car axle, a belt driven therefrom, an electric generator 40 driven by said belt, an automatic switch for making and breaking the external circuit of said generator, a source of

sand, a shunt wound electric motor connected to said generator on the side of said automatic switch adjacent thereto, and a 45 vane adapted to be operated by said motor, to alternately remove a quantity of sand from said source, and feed it to said belt to prevent substantial slipping thereof.

15. In apparatus of the character described, in combination, a railway car, steam pipes therein, a driving belt connected to an axle of said car, a sand reservoir within said car and adjacent said steam pipes, a conduit connecting said 55 reservoir to said belt, and means originally deriving energy from the movement of the car adapted to feed sand through said conduit to the belt.

16. In apparatus of the character described, in combination, a railway car, a source of current, a driving belt connected to an axle of said car, a sand reservoir conveyor operated by energy derived from said source of current to transport sand for said 65 belt and a hand operated switch adapted to connect or disconnect said conveyor and said source of current.

17. In apparatus of the character described, in combination, a railway car, a 70 generator, a driving belt therefor, connected to an axle of said car, a sand reservoir, a conveyor for transporting sand for said belt, an electric motor deriving current from said generator, and connected to continuously operate said conveyor, and a hand operated switch, accessible from said car, for making and breaking the circuit connecting said generator and said motor.

In testimony whereof, we have signed our 80 names to this specification this 3rd day of December 1918.

WALTER L. CONWELL
WILLIAM I. THOMSON.
